UNITED STATES PATENT OFFICE.

MORRIS A. FEINSTEIN, OF CHICAGO, ILLINOIS.

HEEL.

Application filed October 5, 1925. Serial No. 60,468.

The invention relates to heels and more particularly to wooden heels which are employed for ladies' shoes and are covered by satin, leather or other material adapted to give the heel a neat appearance.

It is an object of the invention to provide a heel of the character specified where a rubber lift is secured to the heel in such manner that during wear the covering of the heel is not displaced or shifted, thereby retaining the finished and neat appearance of the heel throughout the use of the shoe to which the heel is secured.

A further object aims at providing means for permitting a rubber lift to be secured to a covered wooden heel so that the junction of the heel at the lift is secure against the entrance of foreign substances.

A still further object aims at providing comparatively inexpensive means for preventing foreign substances from entering the junction between a wooden heel and the rubber lift attached thereto.

With these and other equally important objects in view the invention comprises the means described in the following specification, particularly pointed out in the claims forming a part thereof, and illustrated in the accompanying drawing, in which:

Fig. 1 is partly section, partly side view of a wooden heel constructed in accordance with my invention;

Fig. 2 is a detail section.

As well known, wooden heels used for ladies' shoes are covered with satin, soft leather or other pliable material adapted to give the heel a finished and neat appearance.

Such covering surrounds the entire heel, but a small strip overlaps the edges of the heel bottom and is secured thereto by glueing or in any other preferred or approved manner. In securing a rubber lift to the heel in the ordinary manner, such as by nails, the resiliency of the rubber transmits certain strains and thrusts onto the bottom, causing a dislocation of the covering fastened to the heel bottom. In addition, foreign matter can easily enter between the heel and the lift thereby eventually loosening the lift.

In accordance with my present invention, these difficulties are entirely obviated.

Referring to Fig. 1, 10 designates a wooden heel which is covered by a layer of fabric or leather 11 and which intimately hugs the heel and completely conforms to the contour thereof. The fabric 11 is drawn around the bottom edges of the heel and terminates adjacent thereto as indicated at 12. To this heel is secured a composite lift generally indicated by 13, which comprises a lift 14 of rubber or rubber composition to which is vulcanized a thin disk of fiber 15. The composite lift 13 is secured to the heel by nails (not shown) or in any other approved or preferred manner. When so secured the lift 13 slightly protrudes beyond the thickness of the heel and the heel is then cut down to conform to the cross section of the heel. Subsequently the heel is subjected to a buffing operation which causes a compression of the fiber disk at the edge and a slight spreading of the same as indicated at 16. This spreading of the fiber disk entails a sealing effect at the junction of the rubber lift and the heel bottom thereby efficiently preventing foreign substances from wedging between the heel and the lift.

From the foregoing follows that the composite lift insures sufficient resiliency during walking and at the same time provides rigidity at the heel bottom to prevent dislocation of the covering. Furthermore, the improved heel effectively obviates the possibility of foreign substances wedging between the heel and the lift.

While the drawing discloses a preferred embodiment of the invention, various changes and alterations may be made without departing from the purview of the invention. I, therefore, do not limit myself to the details of construction, as shown, nor to the materials used, but include all changes and variations constituting departures within the scope of the invention as defined in the appended claims.

I claim:

A heel, including a body portion, a covering therefor drawn around the bottom edges of said body portion, a resilient lift secured

to said body portion, and a compressible member interposed between said lift and said body portion having an upset outer edge for preventing displacement of said covering on the heel bottom during wear and sealing the junction between said lift and said body portion, said upsetting being effected during the

compression of the protruding portion of the compressible member during the buffing operation to which the assembled heel is subjected to. 10

In witness whereof I affix my signature.

MORRIS A. FEINSTEIN.
